CARD AND DISPLAY HOLDER

Frederick L. Wertz, Montclair, N. J.

Application July 2, 1936, Serial No. 88,692

5 Claims. (Cl. 40—11)

This invention relates to card or display holders and it has for one of its objects the provision of means for holding a show card or other display card in a substantially upright position.

5 One of the more specific objects of the invention is to provide a holder of the class described comprising a card-holding clip and a detachable foot or support therefor, the separable nature of which device makes it convenient to ship and easy to store when not in use.

10 Another object of the invention is the provision of a card-holding clip having a card-receiving slot of resilient nature adapting the clip to receive cards of various thickness.

15 Still another object of the invention is the provision of a card-holding clip having means for automatically aligning the card with the longitudinal dimension of the clip so as to give the associated card and clip a neat and attractive appearance.

20 A further object of the invention is the provision of a card-holding clip with detachable support, reversible in nature whereby it can be used either on the right or on the left side of the card.

25 Other objects of the invention relate to the specific details of the clip and of the support as will appear as the following description of the preferred embodiment of the invention proceeds.

30 In the drawing which accompanies and forms a part of the following specification and throughout the several figures of which the same characters of reference have been employed to designate identical parts:

35 Figure 1 is a perspective view of a card supported on both sides by one of the card or display holders forming the subject of the present invention;

Figure 2 is a perspective view of the card-holding clip;

40 Figure 3 is a cross section taken along the line 3—3 of Figure 2;

Figure 4 is a section taken along the line 4—4 of Figure 3; and

45 Figure 5 is a section through the foot of the clip illustrating the correlated structure of the clip and detachable support.

50 Referring now in detail to the several figures, the numeral 1 represents in general the clip which preferably is made from a sheet metal blank folded as is clearly shown in Figure 3 to form a front face 2, and a side face 3, said faces being preferably flat, arranged at right angles to one another, and having a bead 4 extending along the apex of the dihedral angle formed between the front and side faces. The side face 3 opposite the bead 4 is

bent so as to form a corresponding bead 5, the last named bead merging into a curved back face 6 which approaches the front face 2 preferably leaving a very narrow space 7 between said faces for the insertion of a card. The back face 6 is 5 preferably of resilient nature so that cards of various thickness can be slipped into the space 7 and clamped between the front face 2 and back face 6. Said back face preferably has a flaring lip 8 to facilitate the insertion of the card.

10 At both the upper and lower ends of the clip the side and back faces together with the beads 4 and 5 form sockets 9, one of which is shown in Figure 5. The support comprises a rod or wire 10 having a straight portion 11 and a loop or 15 bight 12 which is somewhat resilient and fits frictionally within the socket 9. Due to the resiliency of the loop or bight 12 it bears against the inner surfaces of the beads 4 and 5 and holds the support in fixed relation with respect to the clip 1. Since the sockets at the upper and lower ends of 20 the clip are similar the support may be engaged in either one adapting the clip to be used with either end as the bottom end, this enabling the clip to be reversed and used at the opposite side 25 of the card.

30 In order somewhat to relieve the stiffness of the curved back face 6 and for another purpose which will presently be described, the back face is stamped out or slotted as illustrated in Figure 2, back of the flaring lip 8 with two transverse slits 13 and 14 and a joining slit 15. This confines the stiffness of the back face 6 substantially to those parts which lie above and below the slotted intermediate portion. The tongue 16 formed by the slitting is preferably flattened out as shown in Figure 3 so as to obstruct the passage of the card preventing it entering into either of the upper or lower sockets 9. If it were not for the obstructing tongue 16, the card could be pushed in until its lower corner engaged the loop or bight 12 of the wire which occupies the lower part of the socket, but the upper part could be pushed still further until it contacted the inner surface of the face 3. This would cause the card to be inclined with respect to the longitudinal edges of the various faces of the clip and produce a bad appearance. According to the structure of the present invention, the tongue 16 forms a straight edge and aligns the card to a position in which its side edge 45 is parallel to the longitudinal edges of the clip. 50

55 The card and display holder can be used singly, on either side of a card or in pairs as indicated in Figure 1. The detachability of the support 10 from the clip 11 permits a number of pairs to be 55

arranged in parallel in a small package facilitating the sale and storage of the article. It is obvious that the construction of the clip or the support for that matter is not confined to metal, 5 but the clip may be made of any eligible sheet material such for example as celluloid, bakelite, etc.

While I have in the above description disclosed what I believe to be a preferred and practical 10 embodiment of the invention, it will be understood to those skilled in the art that the details of construction and the specific form and arrangement of parts is merely by way of example and not to be construed as limiting the scope of 15 the invention which is defined in the appended claims.

What I claim is:

1. Card and display holder comprising a sheet material clip and a supporting base therefor, said 20 material being bent to form front and side faces substantially at right angles to one another, and a curved back face approaching the front face, with flaring lip, the curve of said back face being substantially tangent to (perpendicular planes 25 parallel respectively to said side and front faces and spaced therefrom, whereby said back face forms with said side face a socket and with said front face a card-receiving slot, and a support for said clip having a portion fitting said socket.
- 30 2. Card and display holder comprising a sheet material clip, said material being bent substan-

tially at right angles to form front and side faces with a bead along the apex of the angles between said faces, and having a curved resilient back face approaching the front face, with flaring lip, to form with said front face a card-receiving slot, and a support for said clip comprising a rod having a looped portion adapted to fit frictionally within a socket formed between said back and side faces and including said bead. 5

3. Card and display holder comprising a sheet 10 material clip, said material being bent substantially at right angles to form front and side faces, with a bead along the apex of the angle, and having a curved resilient back face approaching the front face, with flaring lip, to form with 15 said front face a card-receiving slot, said back face being intermediately slotted to form a tongue, said tongue extending into the base of said slot in obstructive relation to said bead, determining the parallel alinement of said inserted card relative to the longitudinal dimensions of said clip. 20

4. Card and display holder as claimed in claim 3 including a support at the foot of said clip.

5. Card and display holder as claimed in claim 3, said clip having a similar socket at each end, 25 formed between said back and side faces and including said bead, and a support including a portion adapted to fit into either of said sockets whereby said clip may be reversed.

30

FREDERICK L. WERTZ.
